UNITED STATES PATENT OFFICE.

DANIEL J. BARRETT, OF WATERBURY, CONNECTICUT.

COMBINED WINDOW-SHADE BRACKET AND CURTAIN-ROD SUPPORT.

1,183,519.

Specification of Letters Patent. Patented May 16, 1916.

Application filed March 22, 1916. Serial No. 85,879.

To all whom it may concern:

Be it known that I, DANIEL J. BARRETT, a citizen of the United States, residing at Waterbury, in the county of New Haven 5 and State of Connecticut, have invented a new and useful Improvement in Combined Window-Shade Brackets and Curtain-Rod, Supports; and I do hereby declare the following, when taken in connection with the accompanying drawings and the characters 10 of reference marked thereon, to be a full, clear, and exact description of the same, and which said drawings constitute part of this application, and represent, in—

15 Figure 1 a face view of a pair of window shade brackets and curtain rod supports constructed in accordance with my invention. Fig. 2 a side view of one of the devices.

20 This invention relates to an improvement in combined window shade bracket and curtain rod support, the object being to provide brackets which may be secured to a window casing with minimum amount of 25 damage to the casing due to securing devices and to provide a support for tubular curtain rods having bowed ends or goose necks; and the invention consists in the construction hereinafter described and particularly recited in the claims.

30 In carrying out my invention, I form the window shade brackets from strips of metal 2 the upper ends 3 of which are turned rearward and provided with downwardly projecting prongs 4 adapted to be driven into the top of the window casing. At the lower end of the strips are perforations 5 for the passage of nails or screws by which the strips are rigidly held in place. Two strips 35 are provided for each window and their inner edges are provided with window shade brackets 6 and 7 formed integral with the plates and projecting outward at right angles thereto, these brackets being formed 40 in the usual manner for supporting window shade rollers. The outer edges of the brackets are formed with integral arms 8 which

project upward in the plane of the plates 2 and then outward and upward therefrom so as to throw the upper ends 9 of the arms 50 outward beyond the plane of the plates 2, and these upper ends are rolled or formed with tubular bearings for the ends 10 of a tubular curtain rod 11. This curtain rod 11 may be telescoped so as to be adjusted 55 longitudinally. Preferably, and as shown, the tubular ends of the arms will be tapered so that the ends of the curtain rod will closely fit thereon. By setting the curved ends of the curtain rod over the tubular 60 ends of the arms 8 they will be firmly held in place and not liable to become accidentally detached. The curtain rod support is placed in position at the same time the window brackets are secured in place. The 65 combined window shade bracket and curtain rod support are formed from sheet metal and can be produced at very low cost for manufacture.

I claim:—

1. A combined window shade bracket and curtain rod support comprising plates turned inward at their upper ends and formed with downwardly projecting prongs, 70 said plates formed on one edge with outwardly projecting integral window shade brackets, and at their opposite edges with upwardly and outwardly extending arms, said arms provided at their outer ends with tubular rod-supports over which the ends 75 of a curtain rod may be passed.

2. A combined window shade bracket and curtain rod support comprising plates turned inward at their upper ends and formed with downwardly projecting prongs, 80 said plates formed on one edge with outwardly projecting integral window shade brackets, and at their opposite edges with upwardly and outwardly extending arms, 85 said arms provided at their outer ends with tapered tubular rod-supports over which the ends of a curtain rod may pass.

DANIEL J. BARRETT. [L.S.]
